Filed Dec. 23, 1963, Ser. No. 332,352

3 Claims. (Cl. 2—172)

This invention relates to an improvement in caps, and deals particularly with a cap having a resilient insert designed to permit one size of cap to be used on heads of different sizes.

In our previous Patent 2,883,669, issued April 28, 1958, for "Cap," included a rounded dome-shaped body having a visor projecting forwardly from the lower edge thereof. An ear flap structure also encircled the major portion of the cap body and was foldable from a position inwardly of the upper portion of the cap to a downwardly projecting position to serve as a protection for the ears. The ear flap portion is provided with a resilient insert which permitted the ear flaps to fit snugly within the interior of the cap body when not in use, and at the same time was capable of expanding sufficiently to extend over the ears and fit tightly about the back of the head.

Due to the shape and general construction of the cap, the cap was not adaptable for use on heads of different sizes and shapes. As a result, it was necessary to maintain a complete inventory of cap sizes. It is an object of the present invention to produce a cap which is attractive in appearance and yet which is capable of accommodating heads of different circumference and shape.

More recently it has been proposed to produce a cap having a relatively inelastic crown portion which extended upwardly from the visor and across the top of the head, and to provide elastic portions marginally connected to this crown portion which is of sufficient height to be centrally folded to provide an elastic portion of double thickness extending around the major portion of the head and which, in unfolded condition, would serve as a protection for the ears and the back of the lower portion of the head. While such an arrangement produces a cap which will fit a wide variety of head sizes, it is not particularly attractive as the major portion of the cap is formed of knitted fabric similar to that which may be used to produce tassel caps. Furthermore, as the elastic insert extends the full height of the cap to the crown, the more attractive inelastic portion is virtually concealed when viewed from the back. Furthermore, the cap does not hold its shape particularly well due to the fact that the cap is mainly formed of the elastic fabric.

It is an object of the present invention to provide a cap which is attractive in appearance, and which does not deviate materially from caps of conventional style in general appearance. When the flap structure is folded upwardly to encircle the sides and rear of the cap body, the cap is similar in appearance to any cap of the same general shape. At the same time, the portion of the cap which encircles the part of the head which is normally of largest circumference, it is flexible and resilient so that the same cap body may be worn on heads of different size.

A feature of the present invention resides in the provision of a cap which preferably includes an oval shaped crown to which is marginally attached a depending skirt which is normally generally cylindrical. To the lower edge of this cap body portion is provided a flap structure which is also generally arcuate in cross section when in lowered position. This flap structure includes a pair of relatively inelastic side portions which taper from a point of minimum depth at the edge of the visor to a point of maximum depth at its other end. A flexible

2

resilient insert connects the ends of these flap side portions, and the insert extends continuously through the height of the flap structure to terminate at a point intermediate the lower edge of the cap body and the crown of the cap. This insert, which is generally approximately rectangular, thus serves as a connection between the rear ends of the flap portions and fills a notch in the lower edge of the body portion at the rear thereof which may expand to accommodate heads of various sizes.

An important feature of the present invention resides in terminating the resilient section of the cap at a point spaced below the connection of the crown with the encircling body of the cap. As a result, the distance between the top of the elastic insert and the line of fold connecting the flap structure to the cap body is less than the depth of the flap structure. Accordingly when the flap structure is folded upwardly in the position in which the cap is usually worn, the portion of the elastic insert extending into the cap body is completely concealed and only the inelastic material of the hat body is visible above the flap structure.

We have found that the size of the oval shaped crown and the portion of the inelastic material immediately adjoining the crown need not vary to any great extent in fitting a wide variety of head sizes. The portion of the head which is of greatest circumference insofar as the cap is concerned is usually located near the lower edge of then cap body when the cap is in place. As a result, the elastic insert may terminate at some distance below the crown of the cap without greatly limiting the variation in sizes of heads the cap will accommodate.

These and other objects and novel features of the present invention will be more clearly and fully set forth in the following specification and claims.

35 In the drawings forming a part of the specification:

FIGURE 1 is a front perspective view of the cap with the ear flaps folded upwardly.

FIGURE 2 is a rear perspective view of the cap shown in FIGURE 1.

40 FIGURE 3 is a rear perspective view of the cap with the flaps in lowered position.

FIGURE 4 is a side elevational view of the cap.

FIGURE 5 is an enlarged vertical sectional view of the cap, the position of the section being indicated by the line 5—5 of FIGURE 3.

45 FIGURE 6 is a sectional view through a portion of the cap, the position of the section being indicated by the line 6—6 of FIGURE 3.

FIGURE 7 is a sectional view through a detail portion 50 of the cap, the position of the section being indicated by the line 7—7 of FIGURE 3.

The cap which is illustrated in the drawings is illustrative of the preferred construction of the present invention. In general, the cap A includes a generally oval crown 10 which is formed of generally inelastic material 55 such as fabric, leather, imitation leather and the like. The crown 10 is marginally secured by stitching 11 to a depending skirt portion 12 which is generally cylindrical in shape and includes a forward portion 13 and side portions 13A and 13B which extend throughout the major portion of the circumference of the crown 10 and which defines the depth of the cap and a relatively shorter rear portion 14 which is connected at its ends along seams 15 to the rear edges of the front portion 13. If preferred, the cylindrical body portion 12 can be formed in one piece with a rectangular notch generally numbered 40 cut from the rear thereof.

70 The forward portion 13 of the head body is secured along a seam 16 to a visor 18 which normally includes an upper layer, a lower layer, and an intermediate stiffening portion, not illustrated in detail in the drawings. The remainder of the circumference of the lower edge of

the hat body portion 12 is connected to an ear muff structure 17 which includes a pair of side members 19 which taper in thickness at the forward end as indicated at 20, this forward end being secured between the edge of the visor and the cap body. As indicated in FIGURE 7 of the drawings, the side portions 19 normally include an outer covering 20 and a contiguous or substantially contiguous inner layer 21 which may be of fur or other warm material which provides a decorative appearance when the cap is worn with the ear flaps raised, and which act as a protector for the ears when the ear flaps are lowered.

As indicated in FIGURE 5, a crown liner 22 which normally fits the contour of the crown piece 10 underlies the crown but is not attached thereto. The marginal edge of the crown liner 22 is stitched as indicated at 23 to the body liner 24 which follows the contour of the cap body and is usually provided with a front portion 25 which lies inwardly of the front portion 13 of the cap body and a shorter rear portion 26 which lies inwardly of the rear portion 14, of the cap body. The front and rear portions 25 and 26 are connected along a seam 27 which is free of attachment with the outer cap body. The lower edge of the front portion 25 of the liner is secured to the lower edge of the forward portion 13 of the cap body at the point of attachment with the sides 19 of the earmuff structure. The seam being covered by a tape or band 29 which forms the sweat band of the cap and which extends throughout the length of the forward portions of the body and liner.

A generally rectangular resilient section 30 forms the rear of the cap body and the rear of the ear muff portions. The resilient section 30 includes an inner layer 31 which is stitched or otherwise secured as indicated at 32 to the lower edge of the liner portion 26, and an outer layer 33 which is stitched or otherwise secured as indicated at 34 to the lower edge of the rear body portion 14. The two layers 31 and 33 are foldably connected as indicated at 35. It will be noted that in preferred form, the inner layer 31 is free of connection with the crown or body portion of the cap. As indicated in FIGURE 6 of the drawings, the inner panel 31 of the elastic section is connected to the liner portion 25 by stitching such as 36, and the outer panel 33 is connected to the outer panel 13 of the body portion along rows of stitching 37. This is not true of the lower portion of the cap where the resilient panels 31 and 33 are connected to the outer flap portion 20 and inner flap portion 21 along a single area of stitching 39. It will be noted that the resilient section includes inner and outer parts, the upper portions of which are free to flex individually so that the upper portion of the resilient section may flex the liner to fit the contour of the head. Usually the lower edge of the cap body portion 12 encircles the head where it is of greatest circumference. As a result, it is not necessary to make the rear portion 14 of the hat body resilient and no useful purpose is accomplished in doing so. At the same time, the resilient section includes at least the lower one-half of the rear wall so that the resilient section may expand or contract to fit the circumference of the head. When the ear flaps are folded upwardly as illustrated in FIGURES 1 and 2 of the drawings, only the inelastic portion of the cap exterior is visible above the flaps, greatly improving the appearance of the structure over caps which have an elastic insert extending to the cap crown.

In accordance with the patent statutes, the principles of construction and operation of this improvement in caps have been described, and while an endeavor has been made to set forth the best embodiment thereof, it should be understood that changes may be made within the scope of the following claims without departing from the spirit of the invention.

We claim:

1. A cap including, a cap body including a crown and front and side portions terminating at their lower edges along a substantially common plane, and a rear portion terminating intermediate the crown and said common plane to define a generally rectangular notch at the rear of the body, a visor secured to the lower edge of said cap body opposite to said notch, side flaps foldably secured to the lower edges of said cap body between said visor and said notch and terminating in substantial alignment with the sides of said notch, a cap liner substantially coextensive with said cap body and secured thereto along the lower edges of the front and sides of said cap body, a resilient insert including a pair of generally rectangular panels foldably connected along their lower edges to form inner and outer resilient panels, means connecting the outer panel to the rear edges of the side portions and the rear portion of the cap body but free of connection with said liner, means connecting the inner panel to the liner and free of direct connection with said cap body, said resilient insert terminating on substantially a common plane with the lower edges of said side flaps, and means connecting the sides of said resilient insert to the rear edges of said side flaps.
2. A copy including, a cap body including a crown, and front and side portions secured at their upper edges along a substantially common plane, and a rear portion marginally connected to the remainder of said crown margin and to said side portions, said rear portion terminating intermediate said crown and a common plane of the lower edges of said front and side portions, a visor secured to the lower edge of said front and side portions opposite said rear portion, side flaps foldably connected to the lower edges of said front and side portions between said visor and terminating in substantial alignment with the sides of said rear portion, a cap liner substantially coextensive with said cap body and secured thereto along the lower edges of said front and side portions of said cap body, a resilient insert including a pair of generally rectangular panels foldably connected along their lower edges to form inner and outer resilient panels, means connecting the outer panel to the rear edges of said side portions and to the rear portion of said cap body but free of connection with said liner, means connecting said inner panel to said liner and free of direct connection with said cap body, said resilient body terminating with its folded edge substantially on a common plane with the lower edge of said side flaps, and means connecting the rear edges of said side flaps to the sides of said resilient panels.
3. The structure of claim 2 and including side flap liner panels substantially coextensive with said side flaps and marginally secured thereto.
